UNITED STATES PATENT OFFICE.

RALPH V. L. HARTLEY, OF EAST ORANGE, NEW JERSEY, ASSIGNOR TO WESTERN ELECTRIC COMPANY, INCORPORATED, OF NEW YORK, N. Y., A CORPORATION OF NEW YORK.

CURRENT-MODIFYING RELAY SYSTEM.

Application filed September 23, 1919. Serial No. 325,731.

To all whom it may concern:

Be it known that I, RALPH V. L. HARTLEY, a citizen of the United States, residing at East Orange, in the county of Essex,

5 State of New Jersey, have invented certain new and useful Improvements in a Current-Modifying Relay System, of which the following is a full, clear, concise, and exact description.

10 This invention relates to translating circuits employing translating devices or relays, and more particularly to translating circuits adapted to suppress certain components resulting from the translating opera-

15 tion. The individual translating devices or relays employed are adapted to produce output currents comprising a complex combination of the applied voltages or currents.

In my Patent 1,494,905, issued May 20, 20, 1924, it is shown that for the typical three electrode thermionic relay the output current I may be represented within certain limits by the relation

$$I = \alpha(E + e)^2 \quad (1)$$

25 Where α is a constant depending upon the relay structure, E is an equivalent applied constant voltage which in reality is a function of the plate voltage, grid voltage and such inherent voltages as are present in the 30 relay due to contact differences of potential and voltage drop through the filament if a current heated filament is used as a cathode, and e represents a variable voltage which is 35 impressed on the input circuit.

If the relays are used as modulators in which a carrier wave e_p is modulated by a signal wave or other wave e_q then $e = e_p + e_q$. By expansion,

$$40 I = \alpha E^2 + 2\alpha E(e_p + e_q) + \alpha(e_p^2 + e_q^2) + 2\alpha e_p e_q \quad (2)$$

The first term E^2 may be neglected since it 45 does not contain e and represents only a direct current component. The second term represents amplification of the individual waves e_p and e_q , the third term represents a double-frequency component of both waves and the last term represents a modulation 50 frequency component. The transformations for showing that these terms represent the

55 frequencies stated are given in the copending application above referred to and more fully in the British Patent No. 102,503 of 1917.

If the same waves e_p and e_q are applied to the different relays, there are four different combinations that are possible. They may be applied both in the same sign as $e_p + e_q$ or one or the other or both waves 60 may be reversed, the relation of the waves on the four relays I, II, III, IV, being as follows:

$$\begin{aligned} & \text{I} e_p + e_q \\ & \text{II} e_p - e_q \\ & \text{III} -e_p + e_q \\ & \text{IV} -e_p - e_q \end{aligned} \quad 65$$

Corresponding output currents i_1, i_2, i_3 and i_4 from their relative relays will then be, 70 neglecting the constant term E^2 ,

$$i_1 = 2\alpha_1 E e_p + 2\alpha_1 E e_q + \alpha_1 (e_p^2 + e_q^2) + 2\alpha_1 e_p e_q \quad (3)$$

$$i_2 = 2\alpha_2 E e_p - 2\alpha_2 E e_q + \alpha_2 (e_p^2 + e_q^2) - 2\alpha_2 e_p e_q \quad (4)$$

$$i_3 = -2\alpha_3 E e_p + 2\alpha_3 E e_q + \alpha_3 (e_p^2 + e_q^2) - 2\alpha_3 e_p e_q \quad (5)$$

$$i_4 = -2\alpha_4 E e_p - 2\alpha_4 E e_q + \alpha_4 (e_p^2 + e_q^2) + 2\alpha_4 e_p e_q \quad (6)$$

$$q \text{ b} \alpha_1 = \alpha_2 = \alpha_3 = \alpha_4 = \alpha, \quad i_1 + i_2 + i_3 + i_4 = 4\alpha(e_p^2 + e_q^2) \quad (7)$$

and four similar relays connected in this manner would give the double-frequencies of both input waves without transmitting 85 any of the unmodified frequencies and without modulating each other.

If the α 's of all the relays are the same

$$(i_1 + i_4) - (i_2 + i_3) = 8\alpha e_p e_q \quad (8)$$

90 and the four relays connected in this manner would isolate the modulation component and suppress all the other components.

The same principle may be extended, and it is obvious that to suppress all of the components except the double-frequencies of three waves or all except the modulation components of three waves, eight relays 95 would be necessary.

In practice it is very difficult if not impossible to obtain four relays having precisely the same value of α . 100

Taking the different α values into account the equations (7) and (8) become

$$i_1 + i_4 = 2E(\alpha_1 - \alpha_4)(e_p + e_q) + 5 \quad (\alpha_1 + \alpha_4)[(e_p^2 + e_q^2)2e_p e_q] \quad (9)$$

$$i_2 + i_3 = 2E(\alpha_2 - \alpha_3)(e_p - e_q) + \quad (10) \quad (\alpha_2 + \alpha_3)[(e_p^2 + e_q^2) - 2e_p e_q]$$

If the double-frequency component alone 10 is desired the output circuits of the relay combinations are made additive in the sense of (9) plus (10). To retain the modulation components alone the outputs of the relay combinations are opposed.

15 Assuming the tubes have different α values, if these values are known it will be found that for the suppression of any particular components, the tubes can be so chosen as to their α values and so related 20 in pairs as to give a maximum degree of suppression of the undesired components. In each case one of the unmodified frequency components e_p or e_q will be more completely suppressed than the other. 25 However, by making E as small as possible and still have the relation expressed in equation (1) hold, the output of the desired combination-frequency components is not affected and the single-frequency components can be made practically zero.

Fig. 1 of the drawing shows a possible way of associating four thermionic relays I, II, III, IV to secure the double-frequency component alone; while Fig. 2 shows the 35 connection to secure the modulation component alone. These numerals correspond to those used above to indicate the manner of applying the waves e_p and e_q to the respective relays. In the drawing it will be 40 seen that both waves from wave sources 1 and 2 of the waves e_p and e_q respectively are applied in the same manner through the input coils 3 and 4 to the relay I. In the case of relay IV both waves are reversed on 45 the input so that if the outputs of relays I and IV are additive, this connection corresponds to equation (9). In the case of relay II, the wave e_q is applied in reversed direction and in case of relay III, the wave e_p is reversed so that relays II and 50 III with their outputs added correspond to equation (10). If it is desired to retain the double-frequency component alone, the outputs of the relay combinations I and IV and II and III are made additive as indicated by the circuit 5 of Fig. 1 in which the coils 6, 7, 8 and 9 are all connected in the same direction. To retain only the modulation component the outputs of the relay 55 combinations I-IV and II-III are made to oppose which corresponds to subtracting equation (10) from (9). This is accomplished by reversing the connection of coils 8 and 9 with respect to coils 6 and 7 60 as indicated in circuit 10 of Fig. 2.

If the relays are associated and are controlled as above described, keeping the quantity E as small as is consistent with large production of the desired combination frequencies, the waves e_p and e_q may 70 be made to give practically a pure modulated output in circuit 10 or practically a pure double-frequency output if the circuit 5 is used.

The particular relay circuits shown are 75 illustrative of the principle involved and give one way of practicing the invention. The invention is not however, to be limited to the specific means shown but only by the scope of the appended claims.

80 What is claimed is:

1. The method of operating wave distorting repeating devices having a plurality of input circuits and a common work circuit to produce desired wave components in said work circuit, which method comprises simultaneously impressing upon four or more of said input circuits waves of a plurality of frequencies whereby combinations of unmodified-frequency, multiple-frequency and combination-frequency are produced by said devices, suppressing the unmodified-frequency components by impressing them simultaneously upon the common work circuit in such phase relations that their effects are 95 neutralized therein, and simultaneously suppressing the undesired other components by likewise impressing them simultaneously upon the common work circuit in such phase relation as to neutralize their effects 100 therein.

2. The method of operating a plurality of wave distorting repeating devices having a common work circuit to produce desired wave components in said work circuit, which method comprises simultaneously impressing upon four or more of said devices waves of a plurality of frequencies whereby combinations of unmodified-frequency, multiple-frequency, and combination-frequency are 105 produced by each of said devices, suppressing the unmodified-frequency components by impressing them simultaneously upon the common work circuit in such phase relations that their effects are neutralized 110 therein, and simultaneously suppressing the undesired other components by likewise impressing them simultaneously upon the common work circuit in such phase relations as to neutralize their effects 115 therein.

3. A plurality of wave sources, a plurality of relays associated with said sources, said relays acting by groups to produce an output wave comprising only multiple-frequency and combination-frequency components, said groups of relays cooperating to produce an output comprising only one of said components.

4. A plurality of wave sources, a system 125 of similar relays each associated with said 130

waves sources for producing a given frequency-component comprising individual relays associated for suppression of certain of the undesired components, and groups of 5 relays for suppressing the other undesired components.

5. A relay system comprising pairs of relays having a circuit common to said relays, wave sources for all of said relays, said 10 sources being differently related to each group of relays and oppositely related to the relays of a group, said relays having their outputs related to said common circuit by groups.

15. 6. A relay system comprising groups of relays having a common output circuit, means for applying a plurality of waves to said system, the relays of each of said groups being connected so as to suppress unmodified-frequency components in said output and the groups being so related to said common output circuit as to suppress other undesired components in said output circuit.

25. 7. A plurality of wave sources, a plurality of relays supplied from said sources and associated in groups having their outputs associated with a common circuit, each relay producing in its output components of 30 unmodified-frequency, multiple-frequency and combination-frequency, the relays of each group producing zero resultant unmodified-frequency component in said common circuit, each two groups of relays producing zero resultant of another of said components in said common circuit.

8. A plurality of wave sources, a pair of similar three electrode discharge devices connected with said sources, means for varying 40 the grid potential of each device similarly by all waves, the potential variation by said waves being opposite in said devices, another pair of similar discharge devices, means for varying the grid potentials of said second 45 pair differently by the different waves and respectively oppositely by the same wave, output circuits for said devices, and a common circuit for said output circuit related similarly to the individual devices of each 50 pair.

55. 9. A plurality of wave sources n in number, 2ⁿ relays, all said sources being operatively associated with the input of each of said relays in a different manner, each pair of said relays having the wave sources associated oppositely with the relays of said pair, a common circuit for said relays, the outputs of each said pair of relays being similarly associated with said common circuit.

60. 10. A plurality of wave sources, a plurality of relays, all of said sources being operatively associated with the input of each of said relays in a different manner, each 65 wave source being similarly associated with

half of said relays and reversely associated with the other half, each pair of said relays having the wave sources associated oppositely with the relays of said pair, and a common circuit for said relays, the outputs of 70 each said pair of relays being similarly associated with said common circuit.

11. A plurality of wave sources n in number, 2ⁿ thermionic vacuum tube discharge devices each having a cathode, an anode, and an impedance controlling element or grid, all of said sources being operatively associated with the grid-cathode circuit of each of said devices in a different manner, each pair of said devices having the wave source associated oppositely with the grid-cathode circuits of each device of each pair, a common circuit for said devices, the anode-cathode circuits of each of said pairs of devices being similarly associated with said 80 common circuit.

12. A relay system comprising groups of thermionic vacuum tubes each tube having a cathode, an anode and an impedance controlling element or grid, a common work circuit for said tubes, means for applying a plurality of waves to the grid-cathode circuits of said tubes, means connecting the tubes of each of said groups so as to suppress unmodified-frequency components in said 95 work circuit and means connecting the groups to said work circuit in such manner as to suppress other undesired components in said work circuit.

13. A thermionic vacuum tube relay system comprising a plurality of wave sources, a plurality of thermionic vacuum tubes each having an anode, a cathode and an impedance controlling element or grid, a transformer for each wave source connected in 100 series with the grid-cathode circuit of each tube, a common work circuit for said tubes, a transformer to associate the cathode-anode circuit of each tube with said work circuit, means including connections between said 105 first mentioned transformers and other means including connections between said second mentioned transformers whereby both the unmodified frequency components and other undesired frequency components 110 impressed upon said work circuit may be suppressed.

14. In a translating system comprising two mutually related translating devices with input frequencies applied cumulatively 120 with respect to said translating devices and other input frequencies applied differentially with respect thereto, so that the output circuit will contain a component corresponding to the differentially applied 125 frequency, but no component corresponding to the cumulatively applied frequency, a method for suppressing the former component which consists in passing by translation a portion of the input energy to be 130

suppressed around said mutually related translating devices, and superposing the translated energy on the output circuit of the mutually related translating devices in opposite phase relation to the component to be suppressed.

15. In a translating system comprising two mutually related translating devices with input frequencies applied cumulatively with respect to said translating devices and other input frequencies applied differentially with respect thereto, so that the output current will contain a component corresponding to the differentially applied frequencies, but no component corresponding to the cumulatively applied frequencies, a method of suppressing the former component which consists in diverting a portion of the input energy of the frequency or frequencies to be suppressed from the input of said translating arrangement, and impressing said energy upon the output of said translating arrangement in opposite phase relation to the component to be suppressed.

16. In a translating system, a balanced modulator circuit comprising a pair of translating devices, a source of input energy applied cumulatively with respect to said devices, another source of input energy applied differentially with respect thereto, an outgoing circuit upon which the output energy of the modulator is applied, and means to impress upon said outgoing circuit independently of said modulator energy from said differentially applied source.

17. In a translating system, a balanced modulator circuit comprising a pair of translating devices, a source of energy applied cumulatively with respect to said translating devices, and another source of energy applied differentially with respect thereto whereby the output energy of the modulator will contain a component corresponding to the latter source, but no component corresponding to the former source, an outgoing circuit upon which the output energy of the modulator is impressed, and means for impressing upon said outgoing circuit independently of said modulator energy from said differentially applied source with such amplitude and phase relation as to neutralize the effects of the component of the output current of the modulator corresponding to said differentially applied source.

18. In a translating system, a balanced modulator circuit comprising a pair of

translating devices, a source of energy applied cumulatively with respect to said translating devices, and another source of energy applied differentially with respect thereto whereby the output energy of the modulator will contain a component corresponding to the latter source, but no component corresponding to the former source, an outgoing circuit upon which the output energy of the modulator is impressed, an auxiliary translating device, means to apply a portion of the energy from said differentially applied source to said auxiliary translating device, and means to apply the output energy of said auxiliary translating device upon said outgoing circuit in such phase relation as to neutralize the effect of the component of the output current of the modulator corresponding to said differentially applied source.

19. In a translating system a balanced modulator circuit comprising a pair of translating devices, a source of input energy applied cumulatively with respect to said device and another source of energy applied differentially with respect thereto, an outgoing circuit upon which the output energy of the modulator is applied, and means to impress upon said outgoing circuit independently of said modulator energy from one of said applied sources.

20. In a translating system a balanced modulator circuit comprising a pair of translating devices, a source of energy applied cumulatively with respect to said translating devices and another source of energy applied differentially with respect thereto, whereby the output energy of the modulator will contain a component corresponding to one of said sources but no component corresponding to the other of said sources, an outgoing circuit upon which the output energy of the modulator is impressed and means for impressing upon said outgoing circuit independently of said modulator energy from said source corresponding to which there is a component in the output circuit, said last mentioned energy having such amplitude and phase relation as to neutralize the effects of the component of the output current of the modulator corresponding to said last mentioned source.

In witness whereof, I hereunto subscribe my name this 22nd day of September A. D., 1919.

RALPH V. L. HARTLEY.
